Inventor
Carl Hallgren
By Otto M. Kermick Atty.

UNITED STATES PATENT OFFICE

EARL HALLGREN, OF DES PLAINES, ILLINOIS

EDGE-GUIDED SCRIBING GAUGE

Application filed March 3, 1927. Serial No. 172,226.

The invention relates to gauges for use in outlining mortises on doors and door casings for the reception of hinges, locks, etc.

The invention has as one of its prime objects the provision of a construction whereby said device will be guided during the cutting or delineation of the mortise and be prevented against deviation from its course during the delineation of the mortise.

10 Another feature of the invention is the provision of a device of this character with means whereby an edge, such as the edge of a door, may be arranged between said means to thereby hold the device in its proper relation to the door during use of the device in outlining a mortise for a lock at this part of the door.

It is also an object to provide the above mentioned means between which the edge of the door is adapted to be located with elements having cutters, the elements and said means being adjustable relatively to each other to allow the elements of the device to be arranged to permit its use in various other 25 capacities.

It is a further object to provide a device of this character with transversely arranged elements having scribes, the elements being movable relatively to each other and adjustable with respect to said means.

The invention has these and other objects, all of which will be explained in detail and more readily understood when read in conjunction with the accompanying drawings 35 which illustrate one form of which the invention is susceptible, it being obvious that changes and modifications may be resorted to without departing from the spirit of the appended claims forming a part hereof.

40 In the drawings,

Fig. 1 is a front elevation of the device showing it applied to the edge of a door and arranged to outline a mortise for the reception of a lock to be arranged in this portion of the door;

Fig. 2 is an end view of the structure shown in Fig. 1;

Fig. 3 illustrates the structure shown in Fig. 1, the elements being arranged in a changed position and showing it applied for

use in forming a mortise for a hinge in the casing of a door;

Fig. 4 illustrates the device associated with a rabbeted jamb to form a mortise therein; and

Fig. 5 shows the device as applied to the edge of a door to form a mortise therein to receive a hinge.

In the embodiment of the invention illustrated in the drawings, the use of blocks 10 and 11 is contemplated, which blocks provide guides between which the edge of a door may be inserted. These blocks 10 and 11 are mounted upon rods 12 and 13, the blocks and rods being slidable with respect to each other. These rods 12 and 13 are provided with scribes, such as 14, at the opposite ends thereof, the blocks being held with relation to the rods by means of the set screws 15 and 16.

The blocks or guides 10 and 11 provide a means or support for elements 17 and 18 which are also slidable within the blocks. These elements 17 and 18 are also provided with scribing elements 19 and 20 and are employed to provide means whereby a mortise may be outlined in the edge of a door for the reception of a lock. These elements 17 and 18 are adjustable relatively to the guides 10 and 11 so that they may be adjusted to define or outline openings of various sizes to receive locks of different dimensions.

The guides 10 and 11 extend beyond the rods 12 and elements such as 17 and 18, and when applied to the edge of a door will overlap the same and guide and maintain the device in its proper relation during movement thereof while marking the door for the mortise.

The elements 17 and 18 are held in their various positions of adjustment relatively to the blocks or guides 10 and 11 through the medium of the set screws 21 and 22.

From the foregoing description it is manifest that the blocks and rods are all movable relatively to each other and, therefore, will provide a means adaptable for use on doors of various widths and will also allow of adjustment so that mortises of different widths may be delineated upon the edge of the door.

One of the blocks or guides 11 is formed

with a transverse bore 23 within which is located a marker 24 having its opposite ends provided with scribes 25 and 26. The marker 24 is held in various positions of adjustment within the bore through the medium of a thumb screw 27. A slot 28 communicates with the bore and is provided to allow the cutter 26 to travel therein during adjustment of the marker 24.

10 By referring to Fig. 3, it will be evident that the guides 10 and 11 are adapted to be moved relatively to each other so that they may be arranged in the manner shown with the rod 12 projecting a substantial distance 15 therefrom. When the elements are arranged in the manner shown, one of the blocks is arranged so that the side face thereof abuts against a shoulder 29 formed in the door casing, the shoulder forming a guide against 20 which the block may rest while forming a line in the face of the casing. It is, of course, understood that the cutters, such as 19 and 20, provided upon the elements 17 and 18 are arranged so that they point in a direction opposite to that of the cutter provided upon the rod 12 producing the mark.

Fig. 4 illustrates the manner in which the marker 24 is arranged when marking a rabbed jamb for a mortise to receive a hinge at 30 this portion of the door jamb. When the device is arranged in this manner, the face thereof, such as 30, is arranged against the shoulder 31 of the door frame which will act as a guide during the marking of the frame. 35 When it is desired to use the device to mark the edge of a door for the formation of a mortise therein to receive a hinge, the opposite end of the marker 24 is employed, the end being adjusted relatively to the block or guide 40 11 so that the distance from the end of the marker to the opposite face of the door will correspond to the width of the hinge which it is desired to apply to the door and the device will be brought against the face of the door 45 and moved longitudinally thereof, which will cause a mark to be produced in the door along which the material may be removed to form the mortise in the door for the reception of the hinge.

50 From the foregoing description, it is manifest that the rods or bars 12 and 13 provide supports for the blocks or guides, and that these supports may be adjusted relatively to the blocks to compensate for various contingencies with which one may be confronted during the use of the device. It is further evident that the elements 17 and 18 may be adjusted relatively to the respective blocks 55 60 which carry them so that the distance between the ends of these members may be varied. It is also evident that the blocks may be arranged upon the bars so that they assume the position thereof shown in Figs. 3 and 5, and 65 that said blocks may be moved with relation

to the bars to any desired position along their lengths.

From the foregoing description, it is evident that a structure is provided which is particularly adapted for use in providing a delineation in the edge of a door and which positively prevents the device from moving from its proper path during this operation, and produces a device which eliminates any possibility of deviation from a line which the device is adapted to produce, defining the outline of a mortise for the reception of a lock.

Having thus described my invention, what I claim as new and desire to cover by Letters Patent is:

1. In a device of the class described, the combination of a pair of guide members, a support upon which the guide members are movably mounted, shanks each carrying scribing members carried by one of said guide members, said shanks being slidable with their longitudinal axes arranged transversely to each other in said member.

2. In a device of the kind described, the combination of a support comprised of a plurality of relatively movable members having scribing means, a pair of guide members mounted upon the support, elements having scribing means, said elements being mounted in one of said guide members and being arranged transversely to each other and being movable relatively to each other, one of said elements being arranged adjacent an end of the guide member and said guide member having means whereby the scribing means of said last mentioned element may be arranged at various positions between the extremities of said end of the support.

3. In a device of the kind described, the combination of a support, guide members adjustably mounted upon the support, an element having scribing means arranged at one end of one of the guide members and being movable transversely of the guide member, said guide member having means whereby said scribing means may be arranged at various positions between the extremities of said end of the guide member.

4. In a device of the kind described, the combination of a support, guide members adjustably mounted upon the support, an element having scribing means arranged at one end of one of the guide members and being movable transversely of the guide member, said guide member having means whereby said scribing means may be arranged at various positions between the extremities of said end of the support, and an element having scribing means, said element being arranged in said guide member transversely to said first mentioned element and being movable relatively to said guide member.

5. In a device of the kind described, the combination of a support, guide members mount-

ed upon the support, said guide members being movable upon said support relatively to each other, one of said guide members having elements arranged transversely to each other and said elements being movable endwise and relatively to said member, said transversely arranged elements having scribing means, one of said elements being arranged adjacent an end of the guide member and said guide member having a slot in which a scribing means of said last mentioned element is movable.

In witness whereof, I hereunto subscribe my name this 28th day of February A. D., 1927.

EARL HALLGREN.
